UNITED STATES PATENT OFFICE.

HARRY M. KLINGENFELD AND ARTHUR H. INBUSCH, OF MILWAUKEE, WISCONSIN.

MACHINE FOR BREAKING IN SHOES.

1,140,599.

Specification of Letters Patent. Patented May 25, 1915.

Application filed June 2, 1913. Serial No. 771,170.

To all whom it may concern:

Be it known that we, HARRY M. KLINGENFELD and ARTHUR H. INBUSCH, citizens of the United States, and residents of Milwaukee, in the county of Milwaukee and State of Wisconsin, have invented new and useful Improvements in Machines for Breaking In Shoes, of which the following is a description, reference being had to the accompanying drawings, which are a part of this specification.

This invention relates to improvements in machines for breaking in shoes.

It is one of the objects of the present invention to provide a machine for breaking in shoes which is adapted to subject new shoes to substantially the same movements and strains they would get while being worn and thus eliminate the stiffness usually present in new shoes and render them more pliable and thus conduce to the comfort of the wearer.

A further object of the invention is to provide a machine for breaking in shoes which is adapted to approximately imitate the movement of walking and which is desirable as a window display for shoe stores.

A further object of the invention is to provide a machine for breaking in shoes which is of simple construction, is strong and durable and is well adapted for the purpose desired.

With the above and other objects in view, the invention consists of the improved machine for breaking in shoes and its parts and combinations as set forth in the claims, and all equivalents thereof.

In the accompanying drawing in which the same reference characters indicate the same parts in all of the views: Figure 1 is a vertical sectional view of the improved machine for breaking in shoes; Fig. 2 is a front end view thereof; and Fig. 3 is a side view, on a large scale, of one of the yielding lasts used in connection with the machine.

Referring to the drawing the numeral 5 indicates the frame which comprises two spaced side portions 6 having supporting legs 7 and upright standards 8. The side portions are connected together in spaced relation by transverse connecting rods 9 and 10. Horizontal shafts 11 and 12 journaled in side portions have mounted thereon between the said sides, drums or wheels 13 which carry an endless slotted belt 14. The upper horizontal stretch 15 of the belt is

supported on a transverse platform 16 positioned between and connected to the side portions 6. While the belt is shown as a preferred form of movable member which is engaged by the oscillating arms other means may be substituted therefor which will serve the same purpose without departing from the spirit and scope of the invention.

A cranked shaft 17 having opposite cranked portions 18 extends transversely of and is journaled in the upper end portions of the standards 8 and each cranked portion carries a bearing block 19 journaled thereon. 60 Oscillating members 20 having medial slotted portions 21 and upper end slotted portions 22 are mounted on the cranked shaft and the bearing blocks 19 are slidably positioned within the slots 21 of said members. Coiled springs 23 mounted within the medial slots and between which the blocks are interposed, serve to yieldingly hold the said blocks in central position in said slots. The upper connecting rod 10 extends 70 through the upper end slotted portions of the said members to permit said members to slide thereon and oscillate when moved by the cranked shaft.

The lower ends of the oscillating members 20 have jointed lasts 23' pivotally connected thereto which are held yieldingly in proper position by means of springs 24. The springs are secured to the upper edge portions of the lasts and have their free ends 80 bearing against the oscillating members. The lasts are formed with toe joints 25 and with instep joints 26 and springs 27 fastened to the medial sections of the lasts have their outer end portions bearing against the outer sections and permit said joints to yield when the lasts engage the endless belt. The cranked shaft 17 has a belted connection 28 with the shaft 11 and is so driven that when the lasts engage the endless belt they will travel therewith at the same rate of speed and in the same direction. The shaft 11 is provided with a belt wheel 29 for belted connection with a source of power.

In use shoes are placed on the lasts and the machine is started to rotate the endless belt and to oscillate the arms and the lasts carried thereby. The arms in oscillating will for a portion of their travel press the shoes firmly against the endless belt and cause the shoes to bend and give at the lasts joints in a manner similar to the movements

they would get if worn by a person. When thus used on the machine for a short time the shoes will lose their stiffness and become more flexible or "broken in" so that the wearer will be relieved of this undesirable feature when getting a new pair of shoes.

As the oscillating movement of the arms imitate the walking movement the device is 10 very desirable as a window display for advertising purposes.

While the machine only shows a construction for breaking in one pair of shoes at a time it is to be understood that the 15 number of cranked shaft portions and oscillating arms may be increased to break in a greater number of shoes without departing from the spirit and scope of the invention.

What we claim as our invention is:

20 1. A machine for breaking in shoes comprising a frame, a movable member and a movable arm mounted on the frame, and a last movably and yieldingly connected to the arm which is adapted to carry a shoe, 25 the movable member yieldingly engaged by the shoe.

2. A machine for breaking in shoes comprising a frame, an arm yieldingly and movably secured to said frame, a last movably 30 and yieldingly connected to the arm and adapted to carry a shoe, and a member engaged by the shoe.

3. A machine for breaking in shoes comprising a frame, an oscillating arm carried 35 thereby, a last movably and yieldingly connected to the arm and adapted to carry a shoe, and a movable member yieldingly engaged by the shoe.

4. A machine for breaking in shoes, comprising a frame, an oscillating arm carried 40 thereby and having a movable yielding last on its lower end adapted to carry a shoe, and an endless belt mounted on the frame and yieldingly engaged by the shoe and 45 moving in the same direction as the last for a portion of its travel.

5. A machine for breaking in shoes, comprising a frame, an oscillating arm yieldingly carried thereby and having a jointed 50 last on its lower end adapted to carry a shoe, and a movable member yieldingly engaged by the shoe.

6. A machine for breaking in shoes, comprising a frame, an oscillating arm yieldingly carried thereby and having a jointed 55 last on its lower end adapted to carry a shoe, and an endless belt yieldingly engaged by the shoe, and moving in the same direction as the belt for a portion of the travel 60 of the belt.

7. A machine for breaking in shoes, comprising a frame, a cranked shaft mounted 65 thereon, an arm yieldingly connected to and oscillated by the cranked shaft and having a jointed last on its lower end adapted to

carry a shoe, the jointed portions of said last being yieldingly held in position, an endless belt mounted on the frame and yieldingly engaged by the shoe for a portion of its travel, means for supporting the 70 portion of the belt thus engaged, and means for rotating the cranked shaft and the belt.

8. A machine for breaking in shoes, comprising a frame, a cranked shaft mounted thereon, a pair of arms yieldingly connected to the cranked shaft, jointed lasts yieldingly carried by the lower ends of the arms and adapted to carry a pair of shoes, the jointed portions of said lasts being yieldingly held in normal position with relation 75 to each other, an endless belt mounted on the frame and alternately yieldingly engaged by each shoe for a portion of the travel of said last, and means for rotating the cranked shaft.

9. A machine for breaking in shoes comprising a frame, a last movably and yieldingly carried thereby comprising a plurality 80 of parts movably and yieldingly connected together for carrying a shoe, and a member 85 yieldingly engaged by the shoe.

10. A machine for breaking in shoes comprising a frame, a movable member and a movable arm mounted on the frame, and a last comprising a plurality of parts movably 90 and yieldingly connected together, one of said parts being movably and yieldingly connected to the arm which is adapted to carry a shoe, said member yieldingly engaged by the shoe.

11. A machine for breaking in shoes comprising a frame, a last movably and yieldingly carried thereby comprising a plurality 100 of parts movably and yieldingly connected together and adapted to carry a shoe, and an endless belt yieldingly engaged by the shoe.

12. A machine for breaking in shoes comprising a frame, a last movably and yieldingly carried thereby comprising a plurality 110 of parts movably and yieldingly connected together and adapted to carry a shoe, and an endless belt yieldingly engaged by the shoe and moving in the same direction therewith for a portion of its travel.

13. A machine for breaking in shoes comprising a frame, an oscillating arm carried thereby, a last comprising a plurality of parts movably and yieldingly connected together, one of said parts being movably and yieldingly connected to the arm and adapted to carry a shoe, and a movable member 120 yieldingly engaged by the shoe.

14. A machine for breaking in shoes comprising a frame, a last movably and yieldingly carried thereby comprising a plurality 125 of parts pivotally and yieldingly connected together for carrying said shoe, and a member yieldingly engaged by the shoe.

15. A machine for breaking in shoes com-

- prising a frame, a movable yielding last movably and yieldingly carried thereby and adapted to carry a shoe, and a member yieldingly engaged by the shoe.
- 5 16. A machine for breaking in shoes comprising a frame, a movable yielding last movably and yieldingly carried thereby and adapted to carry a shoe, and an endless belt yieldingly engaged by the shoe.
- 10 17. A machine for breaking in shoes comprising a frame, a cranked shaft mounted thereon, an arm yieldingly connected to and vertically reciprocated and oscillated by the cranked shaft, a last carried by said arm and adapted to carry a shoe, and a movable member engaged by the shoe.
- 15 18. A machine for breaking in shoes comprising a frame, a cranked shaft mounted thereon, a plurality of arms yieldingly connected to and oscillated by the cranked
- 20 shaft, means on the frame slidably engaged by said arms, lasts carried by said arms and adapted to carry shoes, and a movable member engaged by the shoe.
19. A machine for breaking in shoes comprising a frame, a cranked shaft mounted thereon, a plurality of arms yieldingly connected to and oscillated by the cranked shaft and having slotted upper ends, means on the frame passing through said slots, 25 lasts carried by said arms and adapted to carry shoes, and a movable member engaged by the shoe.
- In testimony whereof, we affix our signatures, in presence of two witnesses.
